CLAIM

The ornamental design for a flexible cover, as shown and described.

DESCRIPTION

FIG. 1 is a front perspective view of a first embodiment of a flexible cover with front and top flaps in a closed orientation;

FIG. 2 is a front elevational view of the flexible cover of FIG. 1;

FIG. 3 is a rear elevational view of the flexible cover of FIG. 1;

FIG. 4 is a right side elevational view of the flexible cover of FIG. 1;

FIG. 5 is a left side elevational view of the flexible cover of FIG. 1;

FIG. 6 is a top plan view of the flexible cover of FIG. 1;

FIG. 7 is a bottom plan view of the flexible cover of FIG. 1 showing the interior of the flexible cover with the top flap in the closed orientation;

FIG. 8 is a front perspective view of the flexible cover of FIG. 1 with the front flap in a closed orientation and the top flap in an opened orientation;

FIG. 9 is a front perspective view of the flexible cover of FIG. 1 with the front and top flaps in an opened orientation; and,

FIG. 10 is a front perspective view of the flexible cover of FIG. 9, including a phantom outline depicting a fire extinguisher for illustrative purposes.

The phantom lines and areas shown in the figures, including those lines representing stitching, are for illustrative purposes only and form no part of the claimed design. The vertical and horizontal lines shown in FIGS. 1-5 and 8-10 are crease lines.
